A. STRAESSLE.
MASSAGING MACHINE.
APPLICATION FILED APR. 2, 1919.

1,353,809.

Patented Sept. 21, 1920.

UNITED STATES PATENT OFFICE.

ANTON STRAESSLE, OF ZURICH, SWITZERLAND.

MASSAGING-MACHINE.

1,353,809.

Specification of Letters Patent. Patented Sept. 21, 1920.

Application filed April 2 1919. Serial No. 286,852.

To all whom it may concern:

Be it known that I, ANTON STRAESSLE, a citizen of the Swiss Confederation, residing at Zurich, Switzerland, have invented new and useful Improvements in Massaging-Machines, of which the following is a specification.

The present invention relates to a new process for massaging the human and other bodies and to means to carry the new process into practice.

According to the new process adjacent parts of the body receive an oscillating motion by means of two flexible bands which are set into rapid vibration motion in opposite directions to each other.

The parts of the body subjected to the action of the bands act in sympathy with the bands and the rapid to and fro movements produce a very favorable shaking massage on the body, which massage may be intensified to any desired degree of vibration to suit the requirements in the particular cases.

The present invention relates moreover to a new machine for massaging the human body according to the process named, the machine being moreover capable of use for all other known massage treatments with any known implement.

In the accompanying drawings—

Figure 1 shows a sectional elevation of the machine.

Fig. 2 is a section on line 2—2 of Fig. 1. Fig. 3 shows in a diagrammatical manner a second form of the driving gear.

Figs. 4 to 6 show massaging implements partly in section.

The massage machine shown in the drawings comprises an electro-motor 1 which may be of any known construction. The motor 1 is closed at both ends by means of two covers 2, 3 which cover each contains a ball bearing adapted to receive the armature shaft 4. On the one end of the motor shaft 4 I arrange a sleeve 6 adapted to receive the end of a flexible shaft (not shown in the drawings) by means of which the rotations of the shaft 4 which amount to about 2300 per minute may be transmitted to a massage implement. A set screw 7 arranged on the cover 3 holds the covering tube of the flexible shaft. On the cover 3 a ring 8 is provided on which the brush holder for the armature 9 of the electro-motor may be mounted. On the shaft 4 outside the cover

2 there is fixed a spur gear 10 which meshes with a spur gear 11 mounted on a crank shaft 12. The shaft 12 is journaled in the cover 2 and a plate 13 fixed to the cover 2 by means of screws. The crank shaft 12 makes about 1400 revolutions per minute. The end of the shaft 12 projecting from the plate 13 is provided with a sleeve 14 adapted to receive the free end of a flexible shaft 65 (not shown in the drawing) by means of which massage devices may be actuated. A screw 15 arranged on the plate 13 serves to fasten the covering tube of the flexible shaft. The shaft 12 actuates a shaft 19 70 journaled in bearings of the covers 2, 3 by means of a crank rod 17 and a crank 18 on said shaft 19. The shaft 19 projects with both ends over its bearings and carries outside the bearings two stepped cones 20 which 75 are keyed on said shaft 19. An endless belt 33 is placed over both the stepped cones as shown in a diagrammatical manner in Fig. 6. The belt 33 carries two straps 30, 31 which are interconnected by parallel links 80 32 pivoted to said straps 30, 31. To massage the body the straps 30, 31 are laid on the body which presses against said straps whereby the parts of the body partake of the movement of the straps owing to friction. The amplitude of the oscillations is determined by the position of the belt 33 on the stepped cones 20, the stroke of the straps 30, 31 may thus be varied and may be for example either $\frac{1}{2}$ inch, 1 inch, or $1\frac{1}{2}$ inch. 90 The intensity of the action on the body of the patient can be easily regulated by the operator and modified to suit requirements. The parts of the muscles which are oscillated by the straps 30, 31 are near each other 95 and they are moved in opposite directions a very wholesome action is exerted on the muscles which influences all the tissues to the very bones.

The motor 1 which is shown only in a 100 diagrammatical manner may be of any construction to suit the existing voltage and current. On the motor case a switch may be arranged by means of which the motor may be started. The machine requires little 105 space and as the gears are wholly incased the machine may be kept clean.

With the shaft 4 and 12 other massage device may be driven by means of flexible shafts and as the speeds of both shafts are different the massage device may be attached to the suitable shaft. In Fig. 5 a

massage instrument is shown by way of example which is connected to a flexible shaft and which serves to massage the throat. The massage device comprises a handle 35 in which a spindle 36 is journaled. One end of said spindle 36 is connected to the flexible shaft which runs within a covering tube 38 said tube being fastened to the handle 35 by means of a screw 37. On the other end of the spindle a bolt 39 is eccentrically arranged to the axis of said spindle. The bolt 39 of the rotating spindle 36 reciprocates a rod 41 by means of the link 40. The rod 41 is slidably mounted in a casing forming part of the handle 35. The rod 41 is provided at both ends with knobs 42 which are provided with bores adapted to receive pins of a carrier 43 on which a massage implement is adjustably mounted. To vary the speed of the massage tools means for varying the speed of the armature may be employed for instance the brushes may be moved on the ring 8 etc.

Fig. 3 shows in a diagrammatical manner a device to obtain a reciprocating motion from the rotary motion of the shaft 4; which device may replace the crank shaft 12. The device comprises an internally toothed ring 21 fixed to the motor casing concentrically to the shaft 4. On shaft 4 an arm 23 is fixed having at its free end a pin 24 on which a spur gear 25 is journaled. The pitch diameter of gear 25 is half that of the ring 21. On the gear 25 a plate is fastened bearing a pin 26 the axis of which cuts the pitch-circle of the gear 25. On the pin 26 a rod 27 is journaled which receives a rectilinear to and fro movement by rotating the shaft 4 which movement may be used to actuate the band 33 or any other massage instrument. The device has the advantage that the reversal of the rod 27 even at high speeds takes place without shocks, noise and wear being avoided.

Having described my invention what I claim as new is:

1. In a massage machine, a shaft mounted for oscillatory movement and provided with a pair of stepped cones, means to impart rapid oscillatory movement to said shaft and cones, an endless flexible band

engaged with the cones and having its leads arranged in parallel spaced relation and provided with massage elements, and flexible connections between said massage elements. 55

2. In a massage machine, a shaft mounted for oscillatory movement and provided with a pair of cones, means to impart rapid oscillatory movement to said shaft and cones, an endless flexible band engaged with the cones and having its leads arranged in parallel spaced relation and provided with massage elements, and flexible connections between said massage elements. 60

3. A massage machine comprising in combination an electromotor, an oscillating shaft, a gear driving said oscillating shaft by means of the shaft of said electromotor, said gear being housed in the casing of the electromotor comprising an intermediate shaft, means adapted to fix flexible shafts on the armature shaft and on said intermediate shaft, a flexible band adapted to be attached to said oscillating shaft. 70

4. A massage machine comprising in combination an electromotor, an oscillating shaft a gear driving said oscillating shaft by means of the armature shaft of said electromotor, said gear being housed in the casing of the electromotor and comprising an intermediate shaft means adapted to fix flexible shafts on the armature shaft and on said intermediate shaft, a flexible band, stepped pulleys fixed to said oscillating shaft adapted to receive an endless flexible band; parts of which being interconnected by links substantially as described. 80

5. A massage machine comprising in combination an electromotor, an internally toothed ring, a crank on each end of the armature shaft, a spur gear loosely mounted on each crank pin meshing with said toothed ring, the pitch diameter of the spur gear being one half of that of said ring, a pin placed on the pitch circle of said spur gear, a rod loosely mounted on said pin, massaging implements fixed to said rod substantially as described and for the purpose set forth. 90

In testimony whereof I affix my signature.

ANTON STRÄESSLE.
